UNITED STATES PATENT OFFICE

146,625

DESIGN FOR A HOUSE

Robert L. Townsend, Upper Darby, Pa.

Application December 14, 1945, Serial No. 124,754

Term of patent 14 years

(Cl. D13—1)

To all whom it may concern:

Be it known that I, R. L. Townsend, a citizen of the United States of America, residing at Upper Darby, county of Delaware, and State of Pennsylvania, have invented a new, original, and ornamental Design for a House, of which the following is a specification, reference being had to the accompanying drawing, forming a part thereof wherein:

I claim:

The ornamental design for a house, as shown.

ROBERT L. TOWNSEND.
